UNITED STATES PATENT OFFICE.

GEORGE KERN, OF PERU, ILLINOIS, ASSIGNOR TO THE WESTERN CLOCK MANUFACTURING COMPANY, OF LA SALLE, ILLINOIS, A CORPORATION OF ILLINOIS.

ALARM-CLOCK.

No. 890,066.

Specification of Letters Patent.

Patented June 9, 1908.

Application filed January 6, 1908. Serial No. 409,453.

To all whom it may concern:

Be it known that I, GEORGE KERN, a subject of the Emperor of Germany, residing at Peru, in the county of LaSalle, State of Illinois, in the United States, have invented 5 certain new and useful Improvements in Alarm-Clocks, of which the following is a specification.

My invention relates to improvements in 10 alarm clocks and has for its object the production of an alarm clock in which the bell envelops the protecting case inclosing the combined time movement and alarm mechanism, and forming the exposed portion of 15 the clock case. Its further object consists in the novel arrangement, construction and combination of the various parts described and claimed to make a cheap, easily assembled and effective alarm which has a neat 20 and attractive appearance.

In the drawings.—Figure I is a vertical cross-sectional view of my alarm clock, Fig. II is a rear view of my alarm clock, having a portion removed showing the position of 25 movement, the hammer and the shut-off for hammer.

Similar numerals represent similar parts on all the drawings.

In the drawings, 1 is the case which 30 protects the movement 2 from dust and injury. This case is shaped as shown, with a faced part 31 having a number of apertures whose use will be explained below. Case 1 has a rearwardly projecting lip 10, having apertures 35 for the case stem 17 and the legs 30, and which fits the inner circumference of the front 11. Enveloping the case 1 is a bell 5 which is fastened to the rear of said case by means of screws 25, which also secure 40 the hinge fastening 24 for the rear leg 28. 4 is the hammer which strikes bell 5 through the aperture 3 in said case 1. The length of the aperture 3 is regulated by means of a slide 23, which is held to case 1 by means of 45 rivets 22 passing through a slot 21 in said slide 23, and fastened to the case 1. Slide 23 has a handle 20 bent as shown, which enables it to be operated outside of the outer ring of front 11. When this slide 23 is 50 so moved that it partially closes the aperture 3, its lower end obstructs the path of the hammer, locking it against further motion, and thus forms what is called a "shut-off" for the alarm. Bringing this shut-off slide 55 23 to its upper position releases the hammer

4, when it will be free again to strike the bell. The various apertures shown in the rear of the case 1 and bell 5 are used for the winding 60 keys 29 and the various handsets used in all clocks, to pass through.

The movement 2 of my clock is fastened to the dial plate 8 by means of members 6 cut and formed from said dial 8, as shown. 65 Screws 7 secure the movement to these members 6. Dial plate 8 also has projections 9 cut and formed from it, said projections 9 fitting into the apertures in face 31 of case 1. These projections 9 prevent the dial 8 and movement 2 from rotating. Dial 8 is further held against face 31 of case 1 by 70 means of the front 11 which is locked against dial 8 and to lip 10 of case 1 by means of nut 19 on screwed part of case stem 17 passing through slot 16 of front 11, and the legs 30, which are also screwed into 75 case 1. The dial 15 can be fastened to the dial plate 8 by any of the usual means, or it can be made same size as dial plate and locked in place same as dial above described. The front 11 has a curved lip 12 around its 80 aperture 32 which retains the glass 13 and the matting 14 in its proper position. The foot 28 has projections 27 which fit apertures in lugs 26 on hinge 24, and which make it movable against bell so that clock can be 85 packed in a very small space. Ring 18 also is pivotally fastened to case stem 17 and can be laid down to aid in reducing size of package.

It is evident from the above description 90 that my alarm clock can be very easily assembled, that it uses an extremely large bell, which is larger than the movement case and forms the exposed part, enabling me to use an inexpensive case for the movement 95 and at the same time producing a very loud alarm.

I claim:

1. In an alarm, the combination of a protective case having an opening therein, a bell enveloping said case, a hammer operative through said opening to strike the bell, a shut-off slide operative over said opening, a dial plate having projections, a movement fastened to said projections, a front ring, a 100 case stem and legs, said dial plate being held between the case and front by said stem and legs.

2. In an alarm clock, the combination of 105 a protective case having a rearwardly pro-

- jecting edge, an opening in said case, a bell enveloping said case, a hammer operative through said opening to strike the bell, a shut-off slide operative over said opening, a 5 dial plate having projections, a movement fastened to said projections, a front ring mounted on said edge, a case stem and legs, said dial plate being held between the case and front by said stem and legs.
- 10 3. In an alarm clock, the combination of a protective case having a projecting rim, an opening in said case, a bell enveloping said case, a hammer operative through said opening to strike the bell, a shut-off slide operative over said opening, a dial plate having projections, a movement fastened to said projections, a front ring, a case stem and legs, said dial plate being held between the case and front by said stem and legs.
- 15 4. In an alarm clock, a protective case having a faced portion with a rearwardly projecting edge, a front ring mounted on said edge, with means for fastening said ring to said edge, an opening in said case, a bell enveloping said case, a hammer operative through said opening to strike the bell, a shut-off slide operative over said opening, a dial plate having projections, held between 25 said front ring and said protective case, and a movement fastened to said projections.
- 20 5. In an alarm clock, a protective case having a faced portion with a rearwardly projecting edge, a front ring mounted on said edge, with means for fastening said ring to 25 said edge, an opening in said case, a bell enveloping said case, a hammer operative through said opening to strike the bell, a dial plate having projections, a movement fastened to said projections, a front ring, a case stem and legs, said dial plate being held between the case and front by said stem and legs.
- 30

said edge, said means comprising the case 35 stem and the legs, an opening in said case, a bell enveloping said case, a hammer operative through said opening to strike the bell, a shut-off slide operative over said opening, a dial plate having projections, held between 40 said front ring and said protective case, and a movement fastened to said projections.

6. In an alarm clock, a protective case having an opening in the cylindrical part thereof, a shut-off slide concentrically mounted and operative over said opening, a bell enveloping said case, a hammer operative through said opening to strike the bell, a dial plate having projections, a movement fastened to said projections, a front ring, a case stem and legs, said dial plate being held between the case and front ring by said stem and legs.

7. In an alarm clock, a protective case having a rearwardly projecting rim, and an 55 opening in the cylindrical part of said case, a shut-off slide concentrically mounted and operative over said opening, a bell enveloping said case, a hammer operative through said opening to strike the bell, a dial plate 60 having projections, a movement fastened to said projections, a front ring, a case stem and legs, said dial plate being held between the case and front by said stem and legs.

GEORGE KERN.
